BY *Richard Oliver,*

ATTORNEY

UNITED STATES PATENT OFFICE.

MACE A. TUBBS, OF JAMISON CITY, PENNSYLVANIA.

SIGN-BOARD.

1,260,099.

Specification of Letters Patent. Patented Mar. 19, 1918.

Application filed November 27, 1916. Serial No. 133,745.

To all whom it may concern:

Be it known that I, MACE A. TUBBS, a citizen of the United States, residing at Jamison City, in the county of Columbia 5 and State of Pennsylvania, have invented certain new and useful Improvements in Sign-Boards, of which the following is a specification.

This invention comprehends certain new 10 and useful improvements in direction indicators.

The primary object of the invention resides in the provision of a direction indicator which will be of simple and inexpensive 15 construction and in which the directing arms or hands may be adjusted to the proper direction and secured against movement.

Another object of the invention resides in the provision of a device of the above stated 20 character including a post having means upon the same to indicate the different directions and hands adjustably mounted upon the post to properly direct travelers desiring to reach the different cities, towns and vil- 25 lages, the names of which may appear upon the fingers of the hands together with the distance to each place.

With the above and other objects in view 30 as will appear as the nature of the invention is better understood, the same consists in the novel combination and arrangement of coöoperating elements more specifically set forth in the following paragraphs, pointed out in the appended claim and shown in the 35 drawings.

In the accompanying drawings forming a part of this application and in which like designating reference characters refer to corresponding parts throughout the several 40 views,

Figure 1 is an elevation of the complete device.

Fig. 2 is a top plan view thereof with the post in section, and

Fig. 3 is a fragmentary elevation, showing the rear side of the device.

Referring more in detail to the drawings, 1 designates the supporting post, which is preferably provided with the tapered lower 50 end 2, in order that the post may be readily driven into the ground. A suitable head or knob 3 is also provided upon the upper extremity of said post 1. This post serves to support upon its upper portion, the four ra- 55 dially directed and equally spaced direction

indicating arms 4 with the letters 5 positioned upon the same to indicate the four principal directions namely, north, south, east and west, as will be readily understood by referring to Fig. 1 of the drawings. 60

A pair of directing arms or hands 6 are hinged to opposite sides of the post 1 by suitable hinges 7 and are connected by the adjustable links 8 pivoted to the rear sides of said hands 6, as shown at 9 and having the spaced apertures 10 to receive the securing screw 11 when the apertured portions of said rods are crossed. The hands 6 are adapted to be turned to parallel relation with the road or roads to the side of which 70 the post 1 is positioned and each hand preferably has an extended forefinger 13. The names of the cities or towns to which the roads lead may be printed upon the face of the hands with the names opposite or directly upon the fingers and the number of miles at the ends of the fingers or upon the nails thereof. The last city or the one farthest away may be placed upon the uppermost or extended finger while the nearest 80 city may be found upon or opposite the lowermost finger. This, however, is only offered as a suggestion as the names may be arranged in any manner desired.

From the foregoing it will be apparent 85 that parties traveling along the roads where this invention is employed, may readily ascertain the direction to and distance from the different places and will also know the direction in which they are traveling.

While the form of the invention shown and described is what is believed to be the preferred embodiment thereof it is nevertheless to be understood that minor changes 95 in the details of construction and arrangement of parts may be made therein within the scope of the appended claims without departing from the spirit of the invention.

What is claimed as new is:

An indicator including a supporting post, 100 indicating members hinged to opposite sides of said post and normally lying in horizontal alinement with one another and extending in diametrically opposite directions from said post, a link pivotally secured to one side face of each indicating member intermediate the ends thereof, said links having their free ends provided with a plurality of spaced openings extending longitudinally thereof, adapted to overlap in crossed rela- 110

tion so as to bring certain of the openings provided therein into alinement to hold the indicating members at various angular position with respect to one another on said 5 supporting post, means insertible through the alined opening in the links.

In testimony whereof I affix my signature in presence of two witnesses.

MACE A. TUBBS.
